UNITED STATES PATENT OFFICE.

THOMAS WELHAM, OF PHILADELPHIA, PENNSYLVANIA.

IMPROVEMENT IN APPARATUS FOR SPINNING DIRECT FROM THE DOFFER OF CARDING-ENGINES.

Specification forming part of Letters Patent No. 59,106, dated October 23, 1866.

To all whom it may concern:

Be it known that I, THOMAS WELHAM, of the city of Philadelphia, State of Pennsylvania, have invented a new and useful Machine for Spinning Wool, Cotton, or other Material direct from the Doffer of a Carding-Engine; and I do hereby declare that the following is a full, clear, and exact description of the construction and operation of the same, reference being had to the annexed drawings, making part of this specification, in which—

Figure 1 indicates a side elevation; Fig. 2, an end elevation; Fig. 3, a view of the general plan; and Figs. 4 and 5, a sectional view of the spinners.

The letters A indicate the carder; the letters B, the doffer; the letters C, the spinners; the letters D, the spool, motor-shaft, and drawing-roller, around which the spun thread is wound one, two, or more times, so as to draw it from the spinners when spun and feed it to the spools; the letters E indicate the motor-shaft for the spinners C; the letters F, the spool-spindles; the letters G, the frame; the letters H, the spool bed-frame; the letters I, the spools; the letters K, the traversing thread-guide; the letters L, the eccentric that moves this guide; the letters M, the carder's crank-handle; the letters SS, the rollers in spinners C, and between which the thread when spun passes into and through the spinners-cylinder to the drawing-roller D to be spooled.

The spinners C are connected by belts to the motor E, which is also connected by belts to the crank-shaft M, upon which the carder A is affixed. Motion being given to the carder A by the crank M will, by the strapping indicated by the red lines, drive the doffer B, the cylinder E, and the spinners C, placed in front of the doffer B, upon an adjustable bed-frame, R, so as to spin wool, cotton, or other fiber directly from the doffer B. The distance from

the doffer that the spinners C should be placed must be determined by the length of the materials or staple being operated upon. The crank M also gives motion by the strappings indicated by the red lines to the whole machine.

The adjustment of the position of the bed-frame R, I provide for by slots W and set-screw X.

Spinning by this arrangement is direct from the doffer. The material to be spun being held by the rollers S S affixed in the spinners C, is made to pass, when spun, through the cylindrical shaft thereof by the drawing-roller D, from which it is spooled upon the spools I I, affixed upon the spool-staffs F F F.

When yarn of two or more threads is required, the same can be spun by having one or more sets of the spinners C affixed in the rear of the doffer-spinners, but in front of the drawing-roller D, so as to have the yarn, when spun, spooled, as described.

The several parts of this apparatus for spinning direct from the doffer may be made of any material and size suitable.

What I claim as my invention, and desire to secure by Letters Patent, is—

1. The combination, with the doffer B of a carding-engine, of the adjustable spinner-bed R, as and for the purpose described.

2. The combination, with the doffer B of a carding-engine, of the spinners C, constructed and operating as and for the purpose described.

3. The arrangement of the spinners C with inclosed rollers S, the adjustable spinner-bed R, and spools I, operating as herein described, and for the purposes set forth.

THOS. WELHAM.

Witnesses:

I. L. HUSBAND,
WM. H. BUTLER.
